UNITED STATES PATENT OFFICE

HARVEY C. HAYES, OF WASHINGTON, DISTRICT OF COLUMBIA

ACOUSTIC INSTRUMENT

Application filed April 13, 1925. Serial No. 22,637.

(GRANTED UNDER THE ACT OF MARCH 3, 1883, AS AMENDED APRIL 30, 1928; 370 O. G. 757)

My invention relates broadly to acoustic instruments and more particularly to sound reproducing devices employing diaphragms which are driven by electro-magnetic means, 5 and still more particularly to methods and means for reducing the intensity of the various resonant frequencies to approximate equality with the other or non-resonant frequencies so as to render the intensity of the 10 sound output from the diaphragm substantially uniform and independent of the frequency over the working audible range or any predetermined portion thereof.

One of the objects of my invention is to 15 increase the radiation of all frequencies from one side of a sound generating diaphragm through the reaction thereon of the radiation from the other side of the diaphragm, thereby causing the diaphragm to generate 20 practically the same intensity from one side that it normally would from both sides, if they were both allowed to radiate into space.

Another object of my invention is to provide a conical diaphragm sound reproducer 25 in which a selected frequency range of sound vibrations may be reproduced to give substantially uniform intensity.

Still another object of my invention is to provide an arrangement of conical diaphragm 30 sound reproducer in which radiation from the front of the conical diaphragm may be increased while preventing the radiation of sound vibrations from the rear of the diaphragm to prevent the radiation of undesired frequencies.

A still further object of my invention is the provision of an absorbent for undesired frequencies in relation to a conical diaphragm sound reproducer which absorbent may take 40 the form of a filter or reflecting surface arranged parallel to the rear of the conical diaphragm at a distance which may be varied to select the desired frequencies for efficient reproduction.

My invention finds application to large 45 conical diaphragms utilized in the reproduction of sounds and will be described in connection with such diaphragms although it will be understood that the invention is also 50 applicable to other types of diaphragms.

My invention will be more fully understood from the specification hereinafter following by reference to the accompanying drawings, in which:

Figures 1 and 2 show side and front view 55 respectively of a conical diaphragm attached about its periphery to a ring shaped mounting leaving the diaphragm exposed on both sides; Fig. 3 shows schematically that the sound generated on opposite sides of the diaphragm is a half-wave length out of phase; Fig. 4 is a cross sectional view of one of the practical embodiments of my invention, showing the provision of a frequency absorbent material adjacent the rear of the diaphragm 60 for securing the advantages which accrue by the use of my invention; Figs. 5 and 6 show characteristic curves of conical diaphragm constructed in accordance with my invention; and Figs. 7 and 8 show one of the practical embodiments of my invention in a conical diaphragm sound reproducer; and Figs. 70 9 and 10 show still another embodiment of my invention.

The intensity and quality of the sound 75 heard at any point away from a diaphragm which radiates sound on both sides is dependent upon the sum total of the sound originating on each of the two sides of the diaphragm and both the intensity and quality 80 are adversely affected through the process of wave interference. Moreover, the effect upon the ear of such a sound reproducer is unsatisfactory and unpleasant for the reason that the sense of direction operates with difficulty 85 because the sound does not come from a single source but from two distinct sources, one on each side of the diaphragm, and while these two sounds are practically identical as regards location, nevertheless, so far as the 90 sense of direction is concerned they are well separated because they generate sound entirely out of phase. By my invention I provide a diaphragm construction which radiates sound free from undesired frequencies 95 from one side only of the diaphragm.

Referring more particularly to the drawings, reference character 1 designates a cylindrical frame having a concentric ring 2 superimposed thereon for securing a relatively 100

large conical diaphragm 3 in position. I have termed this sound reproducer a "picture frame" reproducer for the reason that its construction, by which radiation of sound is obtained in a single direction only, enables the supporting frame to be readily hung adjacent a wall in the manner of a picture for directing the sound emanations outwardly into a room.

10 In Figure 3, I have illustrated, diagrammatically, the disadvantages arising out of the construction of sound reproducers heretofore employed where emanations of sound occur from opposite sides of the diaphragm. 15 The diaphragm emanates sound represented diagrammatically by reference characters 4 and 5 from the front thereof and simultaneously sound waves displaced 180° are emanated from the rear of the diaphragm 3, as 20 indicated at 6 and 7. By reason of the phase displacement of the sound emanations there will be places indicated at the apex 8 of dotted lines 9 and 10 and the apex 11 of dotted lines 12 and 14 where the emanations will interfere.

25 Figure 4 shows an embodiment of my invention wherein the conical diaphragm 3 is shown clamped between ring shaped members 1 and 2 and one side thereof closed by 30 a wall 15 for preventing radiation of sound from the rear of the diaphragm. Numerals 4 and 5 represent the sound waves radiated from the left or from the exposed side of the diaphragm, and 6 and 7 represent the 35 sound waves generated on the opposite side of the diaphragm. This side of the diaphragm is enclosed from open space by member 15 which is a heavy inert material. Numeral 16 represents an electromagnetic device which 40 drives the diaphragm through link 17 connecting to the center of the cone by small conical members 13. Member 20 is made of a particular sound insulating material, the nature and function of which is dependent 45 upon the physical characteristics of the diaphragm and its driving mechanism and which can be best understood by first assuming it to be made of a material that absorbs no sound energy. Under such conditions the 50 sound waves represented by 6 and 7 will repeat back to the diaphragm and either help or hinder its motion, depending upon the phase relation. If the path of travel from the diaphragm to member 20 and back again 55 is less than one-half of the wave length of the highest pitch sound the diaphragm is called upon to generate, then the reflected wave will always aid the diaphragm on its outward movement and since the energy radiated from the enclosed side of the diaphragm is, barring small viscosity losses, all given back again to the diaphragm its amplitude will increase until the sound generated from the exposed side alone is practically equal to the sound generated from both

sides when both sides are allowed to radiate into space. As a sound generator the device described is superior to that represented by Figs. 1, 2 and 3. Its sensitivity is fully as high and the quality of the sound is better 70 for reasons already stated herein. It still retains one serious defect also contained in the unenclosed diaphragm, viz.: The sound output will be abnormally intense for those frequencies at which the diaphragm or the 75 driver or the combination are mechanically resonant. The purpose of member 20 is to weaken the sound output of these resonant frequencies, and Figs. 5 and 6 illustrate how this is accomplished. In Fig. 5, curve 21 shows the general form of the intensity and frequency curve for a certain type of loud speaker, the ordinates of the curve representing the intensity and the abscissæ representing the frequency, where the diaphragm 80 radiates from both sides.

This is also approximately in the form of the same curve for the enclosed diaphragm as in Fig. 4 and member 20 made of a material having an absorption coefficient so 90 small as to be negligible. Now suppose member 20 to be a perfect absorber for all frequencies between 50 and 4000 cycles. The intensity curve will be represented by the broken line 22 having ordinates equal to approximately one-half the full line curve, for the radiation within the sound chamber is absorbed and does not reflect to help the motion of the diaphragm. If the absorbent represented by 20 is not perfect, or if the absorption varies with the frequency of the sound, then the actual intensity curve will fall somewhere between curves 21 and 22 of Fig. 5, and the ratio of the ordinates will not be constant as shown. If the material were such that its 100 absorption coefficient were greatest for the range of frequencies included between frequencies 400 to 1600 cycles of Fig. 5, and small for the frequencies represented by both ends of these curves, then the shape of the 105 resulting intensity curve would be much more favorable since the higher parts of the curve would be reduced while the lower parts would be affected very much less in proportion.

110 By preventing any small band of frequencies from reflecting back to the diaphragm within the sound chamber it is possible to reduce the diaphragm output for such frequency by about 50 per cent. Any frequency that is absorbed or removed from the chamber by any other method, as for instance, an acoustical filter illustrated more clearly in Figs. 7 and 8, will not reflect to the diaphragm and aid its motion. Thus the decrease in intensity of output for any frequency is equal 115 to one-half the energy absorbed at that frequency and therefore, the present decrease is equal to one-half the coefficient of absorption of the member 20 for sound of that frequency.

Fig. 6 gives a concrete example showing how the final output from a reproducer such as shown in principle in Fig. 4 is modified by the presence of the absorbent 20. Curve 23 gives the output with member 20 removed. Curve 24 shows the coefficient of absorption as a function of the frequency. Curve 25 shows the output intensity plotted against frequency with the absorbent 20 in position. 10 While the combination does not make the intensity uniform irrespective of frequency it does make it more nearly uniform and makes the reproduction noticeably better.

In Figs. 7 and 8 the ring shaped member or casing 1 has been extended to receive a series of resonant chambers 37 formed in a circular plate 36. The circular plate 36 is positioned intermediate plates 34 and 38. Plate 34 has a plurality of apertures 35 concentric with the chambers 37 while plate 38 has apertures 39 disposed along a central axis with respect to chambers 37. The assembly of resonant chambers as illustrated provides a filter system for undesired frequencies wherein undesired frequencies are absorbed and dissipated and not radiated as sound.

In Figs. 9 and 10 I have shown the ring member or casing 1 extended and screw threaded at 30 to receive a rear closure member 31 which may be varied in position with respect to the rear of the diaphragm 3, to such positions as are shown by dotted lines 32 by means of a suitable tool inserted in sockets 33 in the rear of the plate 31. By adjusting the position of the plate 31 I am able to change the length of the path travelled by the sound emanating from the rear of the diaphragm 3. By regulating this distance I am able to annul the undesired frequencies while the desired frequencies may be reproduced. The chamber which encloses the rear side of the diaphragm 3 is so designed and dimensioned that for sound waves therein having the same frequency as those which are unduly weak in the general sound output from the instrument, the path of travel from the diaphragm to the chamber wall 31 and return shall be such that those waves will reflect back and meet the diaphragm in phase. Undesired frequencies are annulled by proportioning the path of travel to be equal to one wave length whereby the reflected frequency strikes the initially generated frequency one half wave length out of phase opposite such frequencies.

While I have illustrated my invention in certain embodiments I desire that it be understood that I intend no limitations upon the invention but that the principle of my invention may be applied in various ways and the advantageous results herein set forth obtained by various constructions of filters, absorbents and other mechanical arrangements associated with the sound reproducing diaphragm and that no limitations upon the

invention are intended other than are imposed by the scope of the appended claims.

The invention herein described may be manufactured and used by or for the Government of the United States for governmental purposes without the payment to me of any royalty thereon or therefor.

Having thus described my invention, what I claim and desire to secure by Letters Patent of the United States is as follows:

1. In an acoustic instrument comprising a sound reproducing diaphragm, a driver for imparting sound vibrations to the diaphragm, a casing secured to the periphery of the diaphragm and forming a chamber enclosing one side of said diaphragm, and means associated with the chamber for regulating and apportioning through selective reactance the extent of the radiation of the various frequencies of the sound energy radiated from the exposed side of the diaphragm.

2. An acoustic instrument comprising a sound reproducing diaphragm, a driver for imparting sound vibrations to the diaphragm, a casing secured to the periphery of the diaphragm and forming a chamber enclosing one side of the diaphragm, the chamber having such proportions that for sound waves therein having a frequency lying near that of the resonant frequency of the diaphragm, the path of travel from the diaphragm to the chamber wall and return shall be such that the waves are reflected to the diaphragm approximately a half wave length out of phase.

3. An acoustic instrument comprising a sound reproducing diaphragm, a driver for imparting sound vibrations to the diaphragm, and a selective frequency absorbing and reflecting medium mounted adjacent to one side of the diaphragm for selectively absorbing and reflecting sound waves produced by the diaphragm.

4. An acoustic instrument comprising a sound reproducing diaphragm, a driver for imparting sound vibrations thereto, a chamber enclosing one side of the diaphragm and dimensioned so that for sound waves therein having a frequency lying at a value removed from the resonant frequency of the diaphragm the path of travel from the diaphragm to the chamber wall and return shall be such that those waves are reflected back and meet the diaphragm in phase.

5. An acoustic instrument comprising in combination a sound reproducing diaphragm a driver imparting sound vibrations thereto, a chamber enclosing one side of said diaphragm and means for varying the effective depth of said chamber for the selection of a depth with which undesired frequencies emanating from said diaphragm may be annulled while desired frequencies may be reinforced and radiated from the other side of said diaphragm.

HARVEY C. HAYES.
